(74) Attorney, Agent, or Firm — Polsinelli PC(57) **CLAIM**

The ornamental design for a connector torque sleeve, as shown and described.

DESCRIPTION

FIG. 1 is a top perspective view of a connector torque sleeve showing our new design.

FIG. 2 is a bottom perspective view thereof.

FIG. 3 is a front view thereof.

FIG. 4 is a back view thereof.

FIG. 5 is a right side view thereof.

FIG. 6 is a left side view thereof.

FIG. 7 is a top view thereof.

FIG. 8 is a bottom view thereof; and,

FIG. 9 is a perspective view thereof.

The broken lines shown in the Figures show portions of the connector torque sleeve that form no part of the claimed design.
